United States Patent Office

Des. 210,980
Patented May 7, 1968

210,980

HYDRODYNAMIC RETARDER

Ray F. Smith, Berwick, Pa., assignor to Berwick Forge
& Fabricating Corporation, Berwick, Pa., a corporation
of Pennsylvania

Filed May 26, 1967, Ser. No. 7,269

Term of patent 14 years

(Cl. D55—1)

FIG. 1

FIG. 3

FIG. 2

FIGURE 1 is an overall perspective view of the retarder showing my new design;

FIGURE 2 is a front view of the retarder shown in FIGURE 1;

FIGURE 3 is a side view of the retarder illustrated in FIGURE 1, the opposite side having substantially the same appearance;

FIGURE 4 is a rear view of the retarder illustrated in FIGURE 1;

FIGURE 5 is a top view of the retarder illustrated in FIGURE 1; and

FIGURE 6 is a bottom view of the retarder illustrated in FIGURE 1.

The dominant features of my design reside in the portions shown in full lines.

I claim:

The ornamental design for a hydrodynamic retarder, as shown and described.
